UNITED STATES PATENT OFFICE.

BENJAMIN STARCH AND EMIL STARCH, OF LA CROSSE, WISCONSIN.

DESIGN FOR A CENTRIFUGAL-SEPARATOR FRAME.

42,309.

Specification for Design.

Patented Mar. 12, 1912.

Application filed November 29, 1911. Serial No. 663,040 $\frac{1}{2}$. Term of patent 14 years.

To all whom it may concern:

Be it known that we, BENJAMIN STARCH and EMIL STARCH, residents of the United States, residing at La Crosse, in the county of La Crosse and State of Wisconsin, have invented a new, original, and ornamental Design for Centrifugal-Separator Frames, of which the following is a specification, reference being had to the accompanying drawing, forming part thereof.

The figure is a perspective of a centrifugal separator frame, showing our new design.

The design is characterized by a base *a* having slightly inclined sides and ends and outwardly curved feet *b* at the corners thereof. At one end of the base is an upright frame, the sides *c* of which are tapered and inclined upwardly with an opening therebetween, and at the upper end of said sides is a cylindrical casing *d*. At the other end of the base is an upright frame having ta-

pered and inclined sides *e* which are spaced apart and terminate at their upper ends in cylindrical portions *f*. A flat or plate portion *g* is formed between the top of the base and frame *c* and a flat or plate-portion *h* is formed between the top of the base and the frame sides *c*, and the top of the base *a* is depressed or recessed as at *a'* between said plate portions. Horizontal cross-walls *c'* and ribs *c''* are formed between sides *c*. A horizontal cross-wall *e'* is formed between sides *e* and a rib *e''* is formed on the inner side of each of said sides.

We claim:

The ornamental design for a centrifugal separator frame, as shown and described.

BENJAMIN STARCH.

EMIL STARCH.
